(57) **CLAIM**

The ornamental design for a case for tablet computer, as shown and described.

DESCRIPTION

FIG. 1 is a front perspective view of the case for tablet computer showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the encircled region in FIG. 1; and,

FIG. 10 is an enlarged detail view of the encircled region in FIG. 2.

The dot-dash broken line markers in FIGS. 1, 2, 9 and 10 delineate portions of the case that are shown enlarged in FIGS. 9 and 10. The dot-dash broken lines form no part of the claim.

1 Claim, 10 Drawing Sheets
